UNITED STATES PATENT OFFICE.

RUSSELL HUFF, OF DETROIT, MICHIGAN, ASSIGNOR, BY MESNE ASSIGNMENTS, TO DODGE BROTHERS INC., A CORPORATION OF MARYLAND.

CRIMPING TOOL.

Application filed July 26, 1921. Serial No. 487,705.

To all whom it may concern:

Be it known that I, RUSSELL HUFF, a citizen of the United States, residing at Detroit, Michigan, have invented certain new and useful Improvements in Crimping Tools, of which the following is a clear, full, and exact description.

This invention relates to metal crimping tools and more particularly to crimping tools for crimping a ferrule or similar article upon a handle or other carrier.

The principal object of the invention is to improve the construction and mode of operation of crimping tools of this type and to produce a tool of comparatively simple construction by which a ferrule or similar article may be crimped upon a carrier in a reliable manner.

With the above object in view, the invention comprises the novel and improved features, constructions and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings, Fig. 1 is a plan view of a tool embodying the invention with certain parts removed to show more clearly the structure;

Fig. 2 is a central sectional view of the tool; and

Fig. 3 is a detail view in elevation of a leaf spring forming a part of the tool.

In the preferred form of the invention illustrated in the drawings, the crimping tool comprises a guide block 2 mounted on a supporting bracket 3 adapted to be secured to a bench or other suitable support. This guide block is formed with an interior guideway, preferably cylindrical in form, in which is mounted to slide axially of the guideway a cylindrical slide block or head 4 which carries the crimping jaws. The slide block 4 is provided with a series of suitably formed guideways in which are slidably mounted a series of jaw carrying slides 6 arranged radially on the slide block. The slides 6 are held in the guideways in the slide block by means of a retaining plate 8. Each of the slides 6 is formed at its inner

end with a crimping jaw indicated at 9 arranged to engage the end of a ferrule or similar article applied to a handle or other carrier.

The cover plate 8 is provided with a central opening 10 through which a carrier with the article to be crimped thereon may be inserted between the crimping jaws.

The slide block 4 is normally held in its upper position with relation to the guide block 2 by means of a coiled spring 12. When the slide block is in its upper position in the guide block, the slides 6 are held in retracted position by means of a spring plate 14 attached to the slide block 4, the upwardly bent arms of which engage respectively projections on the slides 6. The spring plate 14 is secured to the slide block 4 by means of a screw 16, the head of which is arranged to be engaged by the end of the ferrule to be crimped and act as a stop to determine the axial position of the same.

The slides 6 are moved inwardly to carry the crimping jaws together into crimping engagement with the end of the ferrule by the downward movement of the slide block 4 in the guide block 2. During this downward movement of the slide block the outer ends of the slides 6 engage a cam surface 18, preferably conical in form, on the guide block 2, and the slides 6 are thereby carried inwardly together. To enable this movement to be imparted to the slide block, a rod 20 passing through openings in the support 1 and in the base of the guide block 2 is threaded at its upper end into the slide block 4. This rod is connected at its lower end with a hand lever 22 pivoted at 24 on a bracket secured to the support 1.

Fig. 2 of the drawing illustrates a handle 26, such as is commonly used for automobile doors, with a ferrule 28 in place between the crimping jaws 9 of the tool ready for the crimping operation.

In the operation of the tool in crimping a ferrule upon a door handle as shown, the ferrule is placed upon the end of the handle and the handle with the ferrule thereon is inserted through the opening 10 in the cover plate 8 between the crimping jaws until the outer end of the ferrule is engaged with the upper end of the screw 16. This locates the ferrule so that the crimping jaws 9 will engage the inner end

of the ferrule. The lever 22 is then swung downwardly, thereby moving the crimping jaws inwardly together into engagement with the inner end of the ferrule and crimping this end of the ferrule tightly against the handle.

The tool above described is simple, compact and durable in construction and is composed of relatively few parts, so that 10 it may be cheaply manufactured. The device may be readily varied in construction to suit ferrules or other articles of different shapes and dimensions.

It is to be understood that the invention 15 is not limited to the particular construction and arrangement of parts of the illustrated embodiment of the invention, but that the invention may be embodied in other forms within the scope of the claims.

20 Having explained the nature and object of the invention and having specifically described a tool embodying the invention in its preferred form, what is claimed is:

1. A crimping tool having, in combination, 25 a hollow guide block having an interior guideway, a head slidably mounted in said guideway, a series of crimping jaws movably mounted on said head and arranged about and facing toward a central point, 30 means carried by the guide block for moving said crimping jaws inwardly during movement of said head in one direction in said guideway, and a fixed stop on said head to locate the work with relation to the crimping 35 jaws.

2. A crimping tool having, in combination, 40 a hollow guide block having an interior guideway, a head slidably mounted in said guideway, a series of crimping jaws movably mounted on said head and arranged about and facing toward a central point, 45 means carried by the guide block for moving said crimping jaws inwardly during movement of said head in one direction in said guideway, a spring arranged centrally of the tool and having a series of arms extending angularly from the body thereof in the general direction of the axis of the tool for moving the crimping jaws outwardly,

and a stud for holding the spring-plate in 50 position constituting a stop to locate the work with relation to the crimping jaws.

3. A crimping tool having, in combination, 55 a hollow guide block having an interior guideway, a head slidably mounted in said guideway, a series of crimping jaws movably mounted on said head and arranged about and facing toward a central point, means carried by the guide block for moving said crimping jaws inwardly together during the movement of said head in one direction in said guideway, a spring to hold the head normally in position in the guideway with the crimping jaws retracted, and a lever for moving the head against the action 60 of the spring to actuate the crimping jaws.

4. A crimping tool having, in combination, 65 a hollow guide block having a cylindrical guideway, a cylindrical head mounted to slide in the guideway, a series of crimping jaws movably mounted on the head and arranged about the axis of the same, a spring to hold the head normally in position in the guideway with the crimping jaws retracted, yielding means for holding the crimping 70 jaws in retracted positions, a conical cam surface formed on the guide block for moving the crimping jaws inwardly together during the movement of the head in one direction in the guideway, and a lever for 75 moving the head against the action of the spring to actuate the crimping jaws.

5. A crimping tool having, in combination, 80 a hollow guide block having an interior guideway, a head slidably mounted in said guideway, a series of crimping jaws movably mounted in said head and arranged radially about and facing toward a central point, a spring plate arranged centrally of the tool and having arms for holding the 85 jaws normally in retracted positions, means operated by the relative movement of the guide block and head in one direction for moving the jaws inwardly together, and means for moving the head.

95 Signed at Detroit, Mich., this 20th day of July 1921.

RUSSELL HUFF.
